Primary Examiner — Prabhakar Deshmukh(74) *Attorney, Agent, or Firm* — Doherty IP Law Group LLC(57) **CLAIM**

The ornamental design for a speaker pillow, as shown and described.

DESCRIPTION

FIG. 1 is a perspective view of a speaker pillow, showing my new design;

FIG. 2 is a top plan view of the speaker pillow shown in FIG. 1;

FIG. 3 is a bottom view of the speaker pillow shown in FIG. 1;

FIG. 4 is a right side view of the speaker pillow shown in FIG. 1;

FIG. 5 is a left side view of the speaker pillow shown in FIG. 1;

FIG. 6 is a rear view of the speaker pillow shown in FIG. 1; and,

FIG. 7 is a front view of the speaker pillow in FIG. 1. The broken lines illustrate unclaimed portions and form no part of the claimed design.

1 Claim, 4 Drawing Sheets(56)
